DESIGN FOR SHEARS

Clarence L. Mortensen, Dallas, Tex.

Application March 28, 1947, Serial No. 137,980

Term of patent 7 years

(Cl. D22—5)

To all whom it may concern:

Be it known that I, Clarence L. Mortensen, a citizen of the United States, residing in Dallas, in the county of Dallas and State of Texas, have invented a new, original, and ornamental Design for Shears, of which the following is a specification, reference being had to the accompanying drawing, forming a part thereof.

Figure 1 is a perspective view of a pair of shears, showing my new design.

Figure 2 is a side elevational view of the shears shown in Figure 1.

Figure 3 is a plan view of the illustrated shears in their closed position, and

Figure 4 is a side elevational view of the shears in their closed and locked position.

I claim:

The ornamental design for shears, substantially as shown.

CLARENCE L. MORTENSEN.
